UNITED STATES PATENT OFFICE.

FRED E. BRIGHT, OF PHILADELPHIA, PENNSYLVANIA.

TURNSTILE.

1,209,665.

Specification of Letters Patent. Patented Dec. 26, 1916.

Application filed April 6, 1912. Serial No. 688,820.

To all whom it may concern:

Be it known that I, FRED E. BRIGHT, a citizen of the United States, residing at Philadelphia, in the county of Philadelphia and State of Pennsylvania, have invented certain new and useful Improvements in Turnstiles, of which the following is a specification, reference being had therein to the accompanying drawing.

10 This invention relates to turnstiles, and has reference more particularly to that type of apparatus designed to register the number of persons passing through a passageway, and comprising usually a number of 15 rotary arms, which in their movements extend in succession in an obstructing position across the passageway, and which are pushed before the individuals as they pass in succession, the movements of the arms usually 20 actuating suitable registering mechanism.

The object of the invention is to produce an apparatus of simple construction which may be employed in localities where the available space for the installation of the 25 apparatus is limited or contracted, as for instance, the entrance to railway platforms, "pay-as-you-enter" cars, and like locations; and to this end my invention consists in so mounting the arms that after they are swung 30 in an operative obstructing position in succession across the passageway in the direction the individual is moving, they may be shifted by improved means endwise at the 35 end of their swinging movement in succession and in the opposite direction, the result being that the arms will not extend beyond the passageway, so that the device may be operated in a passage no greater in width than the length of the individual arms.

40 In the more specific embodiment of the invention two horizontal arms angularly related to each other, are supported one above the other, so that they may be shifted endwise independently, in the upper end of a 45 vertical rotary column or post disposed at the side of the passageway, the said arms being adapted to be swung in succession across the passageway by being pushed before the persons passing therethrough, and 50 such swinging movements of the arms causing the column to be rotated, means operated by the rotary movement of the column being provided for shifting the arms in an operative position endwise in succession at 55 the end of their swinging movements. As a result of this construction and arrangement

of the parts, each of the arms will be swung in succession in a forward direction through an arc of 180° around the vertical axis of the rotary supporting column, the arms being shifted endwise in a rearward direction between each swinging movement, with the result that the two ends of the arms will be brought in succession to a point coincident with the axis of their swinging movements. 60 65

In the accompanying drawings: Figure 1 is a side elevation of my improved turnstile apparatus. Fig. 2 is a top plan view of the same. Fig. 3 is a vertical sectional elevation of the same. Fig. 4 is a horizontal 70 section taken on the line *a-a* of Fig. 3. Fig. 5 is a horizontal sectional plan view on the line *b-b* of Fig. 1.

In its preferred form, my improved apparatus comprises a vertical column or post 75 1, provided with a flat horizontal circular base 2 which is mounted and guided for rotation, in a fixed base plate 3, the circular base 2 being provided with ratchet teeth 4 (see Figs. 3 and 4) engaged by a spring 80 pawl 4^a, mounted in the base plate 3, so that the column will be prevented from retrograde movement. At its upper end the column is provided with two horizontal guiding openings, a lower one 5 and an upper one 6, extending at right angles to the lower one, these openings being preferably circular in cross section and conveniently formed respectively in cylindrical collars or bosses 5^a and 6^a, firmly fixed to the upper 85 end of the column one above the other and in right angular fixed relations to each other. Mounted in the guiding opening in the upper collar 6^a is an arm or bar 7, adapted to slide endwise freely back and forth in the 90 guiding opening and provided on its end with heads 7^a, 7^b, which serve as stops to prevent the arm from escaping from its guiding opening, and which limit the endwise movements of the arm. A similarly 95 formed bar 8 is mounted in the guiding opening of the lower collar 5^a, and is adapted to slide freely back and forth endwise, this arm being provided in a manner similar to the other arm, with end heads 8^a, 8^b, which similarly act as stops in connection with the 100 ends of the collar in preventing the arm from escaping, and in limiting its endwise movements. These arms are adapted, in the 105 operation of the apparatus, to extend successively in a horizontal obstructing position transversely across the passageway in 110

connection with which the apparatus is used, so that the successive individuals passing through the passageway will push the arms before them, and in this manner will impart a rotary motion to the vertical column. In their actuations, the arms are adapted to be swung in succession through an arc of 180° around the vertical axis of the column, and at the end of each swinging movement, the arms are adapted to be shifted bodily endwise longitudinally and in a direction opposite their swinging movement, the swinging movements of the arms being while they are in an operative position, and the endwise shifting movements of the arms being while they are in an inoperative position.

The swinging movements of the arms are effected by a direct pushing engagement of the individuals, while the endwise shifting movements of the arms are effected by means acting on the arms and controlled by the rotary motion of the column. The preferred means for thus shifting the arms comprises an upright elbow lever 10, having a long vertical pushing arm 10^a, and a short horizontal arm 10^b, the lever being pivoted by means of a horizontal pivot pin 11, between ears 12, extending upwardly from the base plate 3. The end of the short horizontal arm 10^b has mounted on it a roller 14 engaging in a cam groove 15, formed in the side of the base 2 of the column, which groove, at four equidistant points in its circumference, slopes downwardly in the form of a V, so that the cam groove is provided in effect, and as related to the direction of rotation of the column, with four downwardly inclined portions 15^a, 15^a, 15^b, 15^b, and four upwardly inclined portions 15^b, 15^b, 15^a, 15^a, these portions joining each other and the main portion of the groove, and conjointly constituting a continuous cam groove around the circular base 2. As a result of this construction and arrangement of the parts, the roller will, as the column is rotated, be depressed and elevated at intervals corresponding to the location of the deflected portions of the cam groove, and will rock the lever 10 and swing its upright push arm to and fro at intervals. The upper end of the push arm is disposed so that it will in its swinging movements, engage the ends of the arms 7 and 8 after they have completed their horizontal swinging movements around the vertical axis of the column, the swinging movement of the push arm in one direction pushing the actuating arms endwise through their guides, and the swinging movement of the push arm in the other direction causing it to assume its former position.

The relation of the several parts described is such that the forward movement of one of the actuating arms by the passenger from an obstructing position, as shown in Fig. 2,

will throw the push arm in the opposite direction and will then quickly retract the same, the advance of the push arm shifting the preceding inoperative actuating arm endwise in a direction opposite the motion of 70 the passenger, and the retraction of the push arm enabling the operative actuating arm to be swung into position ready itself to be shifted back endwise, the actuating arm first shifted having in the meantime 75 been swung across the passageway to an obstructing position for the next passenger, and assuming said position at the moment that the other actuating arm has taken its position in line with the retracted push arm. 80 To effect these motions in proper sequence, the relation of the deflected portions of the cam groove to the shifting lever and actuating arms is such that when one actuating arm is in an obstructing position, as shown 85 in Fig. 2, the roller on the shifting lever is just ready to enter the downwardly extending portion 15^a of the cam groove, the result being that when the passenger moves said actuating arm before him, the roller will first 90 ride down the portion 15^a of the groove, and then immediately up the portion 15^b, thereby causing the push arm to swing forward at its upper end and retract quickly to its former position, the continued movement of the column, due to the passenger pushing the said obstructing arm before him, causing the roller to travel in the main portion of the cam groove, and thereby holding the push arm in retracted position, and 95 the parts coming to rest after the passenger has left the passageway, with the actuating arm which had been shifted endwise rearwardly in the movements just described, extending transversely across the passageway 100 in an obstructing position ready to be operated by the next passenger.

The movements of the arms as described take place wholly within the limits of the passageway, and at no time do either of the 110 arms project beyond the same; consequently, it is necessary to employ but two actuating arms, and the passageway need not be greater in width than the length of the individual arms. Therefore, the apparatus 115 may be installed in localities where the available space is contracted, and may be contained wholly within such contracted space, between a wall 16 constituting one side of the passageway, and a rail or wall 17, 120 constituting the other side of the passageway.

In order that in the rotation of the column the actuating arms after they have been shifted rearwardly by the push arm, may, 125 when they assume their obstructing positions transversely across the passageway, be maintained in their operative projected positions, I provide a guide 18, which is fixed to the inner side of the wall 16 of the pas- 130

sageway and is formed with a curved guiding surface 18^a in position to be engaged by the end of the arms as they are swung in succession by the turning motion of the column; and by engagement therewith the guiding surface holds the arms in their projected active positions.

The circular base 2 of the column is provided at intervals in its upper side with 10 notches 19^a, 19^b, etc., corresponding in location to the depressed portions of the cam groove, which notches are adapted to be engaged by a latch 20, in order to hold the parts locked when the actuating arms extend 15 transversely across the passageway, this latch being under the control of an attendant, so that he may be enabled to prevent for any reason, the passage of an individual through the passageway.

20 At its upper extremity the rotary column is provided with a journal or stud 21 mounted in a bearing opening in a bracket 22, extending inwardly from the side of the wall 16 of the passageway, for the purpose of 25 affording a proper bearing for the upper end of the column, and insuring its rotation without binding.

It will be understood that the mechanism described may be operatively connected in 30 any suitable manner with any appropriate form of registering or indicating mechanism, for the purpose of registering the number of persons passing through the passageway. I have not shown such connections or mechanism herein inasmuch as my present invention is concerned with the manner of mounting and operating the shiftable actuating arms.

It will be understood further that while 40 I have by way of example shown and described two different forms of my invention, the invention may be embodied in other forms; and it will be further understood that the invention is not limited to any particular form or construction of the parts ex-

cept in so far as such limitations are specified in the claims.

Having thus described my invention, what I claim is:

1. In a turnstile, the combination of a rotary support, barrier arms carried by the support and movable endwise relatively to the same, and a non-rotatable movable lever, actuated positively by the rotary support and disconnected from the barrier arms, said 55 lever adapted in its movements to engage the barrier arms in succession and shift the same endwise.

2. In a turnstile, the combination of a rotary support, barrier arms carried by the support and movable endwise relatively to the same, and a non-rotatable movable member operated automatically and positively by the movable support, and disconnected from the barrier arms, said member acting when 65 operated, to successively engage the barrier arms and move the same endwise.

3. In a turnstile, the combination of a rotary support provided with a cam, barrier arms carried by said support and movable 70 bodily therewith, said arms being movable also endwise relatively to said support, and a movable member operated by the cam and adapted to engage and move the arms endwise.

4. In a turnstile, the combination of an upright rotary support provided with a cam track, barrier arms carried by and movable with said support and movable also relatively to the same, and a swinging lever for 80 moving said arms in relation to the support, the said lever being operated by the cam track in the rotation of the support.

In testimony whereof I have affixed my signature in presence of two witnesses.

FRED E. BRIGHT.
